Primary Examiner — April Rivas*Assistant Examiner* — Jillian Mazzola(57) **CLAIM**

The ornamental design for a Grow Bag, as shown and described.

DESCRIPTION

FIG. 1 is a front, top perspective view of a Grow Bag, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

The broken lines in the figures illustrate portions of the Grow Bag that form no part of the claimed design.
